SHOE SOLE STRAIGHTENER

John D. Corrigan, New York, N. Y.

Application June 13, 1950, Serial No. 167,811

1 Claim. (Cl. 12—129.1)

1

This invention relates to shoe sole straighteners of the kind adapted to be applied to shoes externally thereof for holding the shoe in shape while they are not being worn and, as its principal object aims to provide in a shoe sole straightener of this type an improved construction of such simple form that the device will be inexpensive to manufacture and easy to apply or remove, but will nevertheless be very effective for holding the shoe in proper shape while applied thereto.

Another object of this invention is to provide a shoe sole straightener of the character mentioned which is made from a single length of resilient but relatively stiff wire stock and in which the different portions of the straightener are formed by continuously connected integral portions of such single length of stock and include relatively long arm portions formed by opposite end portions of the stock and a bridge portion which connects the arm portions and is formed by the intermediate portion of the length of stock.

A further object is to provide an improved shoe sole straightener of the kind referred to in which the arm portions extend in crossing relation to each other and in which the lowermost arm portion is offset at the point of crossing.

Still another object is to provide a shoe sole straightener of the character above indicated in which an intermediate portion of the single length of wire forms an upwardly arched bridge connecting the arm portions at one end thereof and engageable with the sole tip and eye-shaped lugs carried by up-turned fingers on the free ends of the arm portions are engageable with the edges of the shank portion of the sole, and in which the sole-engaging portion of such bridge and lugs are formed by flattened portions of the wire stock.

Other objects and advantages of the invention will be apparent in the following detailed description and in the accompanying sheet of drawing in which—

Fig. 1 is a side elevation showing the shoe sole straightener of the present invention applied to a shoe;

Fig. 2 is an end view of the shoe sole straightener and shoe as viewed from the toe end;

Fig. 3 is a bottom plan view of the shoe sole straightener and also showing portions of the shoe in construction lines only; and

Fig. 4 is an end view of the rear end of one of the arms of the shoe sole straightener.

As shown in the drawing, the improved shoe sole straightener 10 is of the type adapted to be

5 applied to a shoe 11 externally thereof by engagement of one end of the straightener with the tip portion 12a of the sole 12 and engagement of the other end of the straightener with the sole portions 12b at the sides of the shank. When thus applied the straightener lies against the bottom of the sole 12 and exerts an upward pressure on the intermediate portion of the sole and a downward pull on the sole tip thereby tending to 10 straighten the sole and prevent the formation of wrinkles in the leather at the top portion 13 of the toe section of the shoe.

The shoe sole straightener 10 is made of wire, 15 as is further explained hereinafter, and comprises an upwardly arched bridged portion 14 at the toe end thereof, a pair of resilient arms 15a and 15b extending rearwardly from the ends of the bridge portion and upturned fingers 16 at the rear ends of the arms and provided with eye-shaped lugs 17. The bridge portion 14 is defined by a forwardly bowed or concave transverse top bar 14a having downturned end portions 14b to 20 which the forward ends of the arms 15a and 15b are joined. The arms 15a and 15b are of a substantial length and extend rearwardly from the bridge portion 14, preferably in crossed relation 25 to each other such that the point of crossing 18 will be at or adjacent the midpoint of the arms and at or near the central point of the sole 12 as shown in Fig. 3, when the sole straightener has 30 been applied to the shoe. At the crossing point 18 the lower arm 15b is offset downwardly to define a confining yoke portion 19, in which the crossing portion of the upper arm is received.

The upturned fingers 16 which carry the eye-shaped lugs 17 are relatively short as compared 35 with the arms 15a and 15b and are of a length such that when the bridge portion 14 is hooked over the sole tip 12a and the rear ends of the arms 40 are pulled upwardly, the lugs 17 will engage over the shank sole portions 12b. The lugs 17 extend laterally inwardly from the fingers 16 in a substantially right angular overhanging relation thereto and when the rear ends of the arms 15a and 15b are pulled upwardly they are also spread apart to permit the lugs 17 to be moved past the sole portions 12b.

The pulling of the rear ends of the arms 15a and 15b upwardly causes the mid-portions of the 50 crossed arms to engage the bottom of the sole 12 and fulcrum thereon in the manner of a lever. When the lugs 17 have been thus moved upwardly past the sole portions 12b and released, the resilient character of the arms 15a and 15b causes 55 the lugs to be swung toward each other and en-

gaged over the sole portions. When the shoe sole straightener 10 has been applied to the sole 12 of the shoe 11 in the manner just explained above, it is retained thereon by the engagement of the bridge and lug portions 14 and 17 with the sole tip and shank portions 12a and 12b, respectively, and by the crossed arms 15a and 15b being pressed against the bottom of the sole. In the applied position of the shoe sole straightener the bridge and the lug portions 14 and 17 exert a strong downward pressure on the tip and shank portions 12a and 12b of the sole 12 to produce the above-mentioned straightening effect on the shoe.

To enable the bridge and lug portions 14 and 17 to engage the tip and shank portions 12a and 12b of the sole more securely, the wire of these portions of the shoe sole straightener is flattened as shown in Fig. 3. The flattened portions of the lugs 17 are designated 17a. The forwardly bowed shape of the flattened transverse top bar 14a also enables the bridge portion 14 to have a greater portion of its length in holding engagement with the sole tip 12a.

It is a feature of the present invention that the different portions of the shoe sole straightener 10, namely, the bridge portion 14, the arms 15a and 15b, the upturned fingers 16 and the lugs 17 are all formed by continuously connected integral portions of a single length of wire stock of a suitable gauge such as for example nine gauge. The wire used is a relatively stiff inherently springy wire, preferably steel wire, which can be bent or formed to the desired shape by suitable tools or dies. For economy of manufacture of the shoe sole straightener 10, the wire stock used should be capable of being readily formed to the shape shown without need for any initial annealing of the wire or any subsequent tempering or hardening treatment.

A type of wire well suited for use in the improved shoe sole straightener 10 is a nickel or other coated steel wire of the kind which is subjected to a drawing operation after the nickel or other coating has been applied. Wire of this kind has a hardness and resiliency which are satisfactory for this shoe sole straightener but still do not prevent the wire stock from being readily bent and formed in suitable dies without need for annealing. The nickel or other coating on the wire stock gives the shoe sole straightener an attractive bright finish without requiring any additional operation and also renders the device resistant to corrosion.

When the shoe sole straightener 10 has been formed to the above-described shape from a single length of a relatively stiff inherently springy wire, as explained above, the bridge portion 14 and the fingers 16, including the lugs 17, will be relatively rigid and unyielding but the arms 15a and 15b will be resiliently flexible and will yield to permit the lugs 17 to be spread apart for engaging or disengaging them with the sole portions 12b. In removing the shoe sole straightener 10 it is only necessary to spread the lugs 17 apart by flexing the arms 15a and 15b whereupon the lugs can be disengaged from the

sole portions 12b. As soon as the lugs have been thus disengaged, the bridge portion 14 can be unhooked from the sole tip 12a.

From the foregoing description and the accompanying drawing, it will now be understood that this invention provides a shoe sole straightener of an extremely simple and economical construction which can be easily applied to a shoe or removed therefrom and which will exert an effective straightening action on the shoe. It will also be seen that this improved shoe sole straightener requires only a single piece of wire stock and that all portions of the device are formed by continuous and integrally connected portions of the single piece of stock.

Having thus described my improvement, I claim as my invention:

A shoe sole straightener comprising, an upwardly arched bridge portion having a transverse concave top bar engageable with the sole tip of a shoe, a pair of relatively long arms connected with the ends of said bridge portion and extending rearwardly therefrom, relatively short upturned fingers at the rear ends of said arms, and laterally inwardly extending eye-shaped lugs carried by said fingers and engageable with edge portions of the sole at the shank of said shoe, said sole straightener being a one-piece structure comprising a single length of resilient but relatively stiff wire stock, said bridge portion being the toe end portion of said single length of wire and said arms being the main portions of said single length which are adjacent to said toe end portion and said finger and lug portions being the shank end portions of said single length, said arms being flexible throughout substantially their full length such as to constitute spring elements adapted to releasably hold said lugs in engaged relation with said edge portions of said sole and such as to be flexibly swingable on said bridge portion to permit spreading of said lugs for applying the straightener to or removing the same from a shoe, the top bar of said bridge portion and the end portions of said lugs being flattened portions of said single length of wire stock, said arms being disposed in crossed relation to each other with the point of arm crossing located at approximately the midpoint of the length of the straightener and the lower of said arms having an offset therein at said point of arm crossing.
